COMBINATION PROPORTIONER AND DISPENSER FOR AMALGAM MATERIALS

Robert C. Angell, Prince Bay, N. Y., assignor to The
S. S. White Dental Manufacturing Company, a corporation of Pennsylvania

Application May 6, 1954, Serial No. 30,364

Term of patent 14 years

(Cl. D24—2)

FIG. 1.

FIG. 2.

FIG. 3.

FIG. 4.

Fig. 1 is a view in perspective showing the top, side and front end of a combination proportioner and dispenser for amalgam materials embodying my new design;

Fig. 2 is a top plan view thereof;

Fig. 3 is a rear end view; and

Fig. 4 is a front end view thereof.

I claim:

The ornamental design for a combination proportioner and dispenser for amalgam materials, as shown and described.
